[57] CLAIM

The ornamental design for a serving counter, substantially as shown.

DESCRIPTION

FIG. 1 is a perspective view of a serving counter showing our new design, the rear and bottom being unornamented;

FIG. 2 is a front elevational view thereof;

FIG. 3 is an enlarged end elevational view taken from the right of FIG. 1, the end opposite being a mirror image thereof;

FIG. 4 is a top plan view thereof.

FIG. 1.

FIG. 2.

FIG. 3.

FIG. 4.
